Primary Examiner—Jeffrey Asch*Assistant Examiner*—Stacia Sinuik*Attorney, Agent, or Firm*—Lyon & Lyon LLP[57] **CLAIM**

The ornamental design for a wheel, as shown and described.

DESCRIPTION

FIG. 1 is a front and side perspective view of a wheel showing my new design; and,

FIG. 2 is a front elevation view thereof.

The surfaces or portions of the wheel not shown in the drawing or described in the specification form no part of the claimed design.

1 Claim, 2 Drawing Sheets*Fig. 1*
